UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

RIVET-SETTING MACHINE.

Application filed March 3, 1926. Serial No. 91,873.

This invention relates to rivet setting machines, and has for its object the provision of an improved drive for the rivet feeding mechanism.

5 The present application is a continuation in part of my prior application Serial No. 49,239 filed on August 10, 1925, in which the rivet feeding mechanism is set forth in detail. In the mechanism referred to the rivets are 10 fed singly by a slide driven by a resilient arm. It is important that the slide be given a positive movement to ensure proper feeding of the rivets, but at the same time the drive must provide enough resilience to avoid 15 breakage in case of a jam.

In the invention herein disclosed a laminated spring is so constructed and mounted as to constitute a firm operating arm that will withstand breakage and at the same 20 time provide enough resilience to protect the rivet feeding mechanism.

While I have disclosed a preferred embodiment of the invention for purposes of illustration, it should be understood that the 25 structure may be modified in various ways without departure from the true spirit and scope of the invention as hereinafter defined and claimed.

In the drawings, 30 Figure 1 is an elevation of part of a rivet setting machine showing the improved rivet feeding mechanism;

Figure 2 is an enlarged side elevation of the resilient driving arm;

35 Figure 3 is a longitudinal section on line 3—3 of Figure 2.

Referring more specifically to the drawings, the rivet setting mechanism is indicated generally at 10. Rivets are fed from the 40 hopper 11 to the rivet setting mechanism by way of the chute 12. The cut-off slide 13 is reciprocated by the resilient driving arm 14 to feed the rivets singly in proper timed relation to the operation of the rest of the 45 machine. The upper end of arm 14 is secured to a lever 15 which is pivotally mounted at 16 and is oscillated by suitable mechanism.

The driving arm 14 is built up of separate 50 spring laminae as shown in Fig. 3. The central two laminae 17 and 18 extend the full length of the arm and are notched as at 19. The lamination 20, which is on the side away from the feed chute 12, is shorter 55 than the central laminae and has its

lower end tapered and bent inwardly as shown at 21. The lamination 22, which is on the side nearest the feed chute 12, is shorter than, but shaped similar to, the lamination 20.

60 The laminations are loosely held together by rivets 25 passing through openings 23 and 24. The lower rivet pulls the outer bowed laminations toward the central laminations thus causing the lower ends of the 65 bowed laminations to resiliently press against the central lamination. As a result of this construction, when the arm 14 is bowed as shown in Fig. 1, the outer lamination will still continue to press against and support 70 the central laminations. The inner lamination is made shorter than the outer to provide a resilient support along the inner radius of the arm when flexed, thereby distributing the strain.

75 The lever 15 is slotted at 26 and the arm 14 is loosely held in the slot by a screw 27 passing through an opening 28 in the arm. The outer end of slide 13 is notched at 29 to receive the forked end of arm 14.

80 It will be noted that the separate laminations comprising the spring arm 14 are not rigidly held at any point. They are entirely free to move with relation to each other or with relation to the rocking lever 15 or the slide 13. At the same time the loose riveting and the manner of attaching the spring to the operating parts causes the laminations to act concertedly as a resilient arm. As the arm is rocked by the lever 15 it positively 85 moves the cut-off slide in both directions of its reciprocation.

85 What I claim is:

1. In a rivet setting machine, a rivet setting mechanism, a rivet supply chute, a cut-off slide cooperating with the rivet supply chute, an oscillatable lever, a laminated spring arm loosely connected to the lever and to the cut-off slide, and means for mounting the laminations of said spring 100 arm so that they are freely movable with relation to each other.

2. In a rivet setting machine, rivet setting mechanism, a rivet supply chute, a cut-off slide cooperating with the rivet supply 105 chute, a laminated spring arm for moving said cut-off slide, and means for mounting the laminations of said spring arm so that they are freely movable with relation to each 110 other.

3. In a rivet setting machine, rivet setting mechanism, a rivet supply chute, a cut-off slide cooperating with the rivet supply chute, a laminated spring arm for moving said cut-off slide, and means for mounting the laminations of said spring arm so that they are freely movable with relation to each other and with relation to the parts with which the arm contacts.
4. In a rivet setting machine, rivet setting mechanism, a rivet supply chute, a cut-off slide cooperating with the rivet supply chute, and a laminated spring arm for moving said cut-off slide having a central lamination and outer laminations the lower ends of which are bowed inwardly against the central lamination.
5. In a rivet setting machine, a rivet setting member, a chute along which rivets move to a position adjacent the operating position of the rivet setting member, a cut-off slide cooperating with the rivet supply chute, an elongated laminated flat spring member having one end in engagement with the cut-off slide for operating the same, a lever pivoted intermediate its ends for actuating the spring, one arm of the lever being longitudinally slotted to provide a seat for the other end of the spring, means for mounting the spring loosely in said slot, and means for oscillating the lever.

In testimony whereof I affix my signature.

EDWIN B. STIMPSON.
